UNITED STATES PATENT OFFICE.

JOHN H. FARRELL, OF NEW YORK, N. Y., ASSIGNOR OF ONE-HALF TO ANTHONY BYRNE,
OF NEW YORK, N. Y.

NON-REFILLABLE BOTTLE.

1,174,839.

Specification of Letters Patent.

Patented Mar. 7, 1916.

Application filed February 17, 1915. Serial No. 8,846.

To all whom it may concern:

Be it known that I, JOHN H. FARRELL, a citizen of the United States, residing at New York city, in the county of New York, 5 State of New York, have invented certain new and useful Improvements in Non-Refillable Bottles; and I do hereby declare the following to be a full, clear, and exact description of the invention, such as will enable others skilled in the art to which it 10 appertains to make and use the same.

This invention relates to bottles and has special reference to a bottle of the type called non-refillable.

15 The principal object of the invention is to improve and simplify the general construction of devices of this character.

20 A second object of the invention is to provide a bottle having a plurality of valves arranged in such relation to each other as to prevent refilling of the bottle.

25 With the above and other objects in view, the invention consists in general of certain details of construction and combination of parts hereinafter fully described, illustrated in the accompanying drawings, and specifically claimed.

30 In the accompanying drawings, like characters of reference indicate like parts in the several views and Figure 1 is a side elevation of a bottle partly in section and showing the valves in position. Fig. 2 is a 35 detail section through the valves and outer valve cage. Fig. 3 is a section on the line 3—3 of Fig. 2. Fig. 4 is a section on the line 4—4 of Fig. 2.

40 In carrying out the objects of this invention I provide an ordinary bottle 10 having a neck 11 provided with a groove 12 just below the mouth. Over this neck is fitted a case 13 of glass, the casing being beaded into the groove 12 while hot and being cemented or welded to the bottle as at 14. This casing is preferably termed the outer 45 neck and the upper part is turned at right angles to the bottle and equipped with a mouth 15 which may be of any preferred form without altering the spirit of the invention, but, which in any event, is slightly 50 larger than the neck 11. Suitably secured,

as by cementing or welding, in this neck 13 is a valve cage 17 wherein is fitted a seat 18 having a beveled inner end 19. Slidable in the cage is a valve 20 arranged to sit upon the seat 18 and the cage is provided 55 with a series of ports 21 in the outer part of said cage these ports being located in the side wall. This outer portion projects into the mouth 15. The valve 20 is of the check valve type and seating on the mouth of the 60 neck 11 is a second valve 22 also of the check valve type. The movement of this latter valve is restricted by the inwardly projecting end 19 of the valve seat member 18.

When the bottle is ready for filling the 65 outer neck 13 has not been applied so that the valve 22 can readily be removed and the bottle filled in the ordinary way. Then the valve 22 is dropped into position and the outer neck with its equipment secured on the 70 inner neck 11. It will be obvious that by tilting the bottle with the mouth 15 downward, the contents will readily flow out while in order to attempt to fill the bottle it will be necessary to turn the mouth 15 75 upward which will result in the valve 20 seating and thus prevent liquid from getting into the body of the bottle.

It is to be noted that it is preferred to 80 make the angular portion of the outer neck 13 through mouth so that the mouth 15 will not project beyond the sides of the bottle and thus making packing and storing easy.

There has thus been provided a simple 85 and efficient device of the kind described and of the character specified.

It will be obvious that many minor 90 changes may be made in the form and construction of this invention without departing from the material principles thereof. It is not therefore desired to confine the invention to the exact form herein shown and described but it is wished to include all such as come properly within the scope of the 95 claim.

I claim—

The combination with a bottle provided with a neck, of a check valve seated in the opening of said neck, a second neck secured to the first neck and having an angularly 100

directed portion terminating in a mouth, a valve cage held in said angular portion and provided with outlet ports, a valve seat member arranged at the inner end of said cage and projecting over the first mentioned valve, and a check valve mounted in the cage and closing said member.

In testimony whereof, I affix my signature, in the presence of two witnesses.

JOHN H. FARRELL.
